(57) **CLAIM**

The ornamental design for a wearable computer, as shown and described.

DESCRIPTION

FIG. 1 illustrates in a top perspective view a wearable computer;

FIG. 2 illustrates in a bottom perspective view the wearable computer;

FIG. 3 illustrates in a right plan view of the wearable computer;

FIG. 4 illustrates a front plan view of the wearable computer;

FIG. 5 illustrates a left plan view of the wearable computer;

FIG. 6 illustrates a back plan view of the wearable computer;

FIG. 7 illustrates a top plan view of the wearable computer;

and,

FIG. 8 illustrates a bottom plan view of the wearable computer.

In the drawings, the broken line showing portions of a wearable computer depicts environment and forms no part of the claim.

1 Claim, 1 Drawing Sheet
